[57] CLAIM

The ornamental design for transverse tibial cutting jig for the implantation of a prosthetic knee, substantially as shown and described.

DESCRIPTION

FIG. 1 is a top plan view of a transverse tibial cutting jig for the implantation of a prosthetic knee of my new design;

FIG. 2 is a rear elevation view of the transverse tibial cutting jig shown in FIG. 1;

FIG. 3 is a front elevation view of the transverse tibial cutting jig shown in FIGS. 1-2;

FIG. 4 is a bottom plan view of the transverse tibial cutting shown in FIGS. 1-3;

FIGS. 5-6 are end elevation views of the transverse tibial cutting jig shown in FIGS. 1-4; and

FIG. 7 is a cross-sectional view taken through FIG. 1 along the line 7—7.
